CLAIM

The ornamental design for a filtration instrument, as shown and described.

DESCRIPTION

FIG. 1 is a perspective view of the filtration instrument showing our new design.

FIG. 2 is a front view of the filtration instrument of FIG. 1. FIG. 3 is a back view of the filtration instrument of FIG. 1. FIG. 4 is a right side view of the filtration instrument of FIG. 1.

FIG. 5 is a left side view of the filtration instrument of FIG. 1.

FIG. 6 is a bottom plan view of the filtration instrument of FIG. 1; and,

FIG. 7 is a top plan view of the filtration instrument of FIG. 1.

The design includes an instrument for tangential flow filtration, which is composed of a stainless steel structure. The front end of the instrument includes a plurality of valves and a pump, with sloping lines between the valves and between valves and the pump. The left and right ends of the instrument include further valves, pumps and lines.
